DESIGN FOR A COMBINED CATCH OPERATOR AND ESCUTCHEON

Earl M. Borchers, Rockford, Ill., assignor to
American Cabinet Hardware Corporation,
Rockford, Ill., a corporation of Illinois

Application August 2, 1944, Serial No. 114,700

Term of patent 7 years

(Cl. D10—8)

To all whom it may concern:

Be it known that I, Earl M. Borchers, a citizen of the United States, residing at Rockford, in the county of Winnebago and State of Illinois, have invented a new, original, and ornamental Design for a Combined Catch Operator and Escutcheon, of which the following is a specification, reference being had to the accompanying drawing, forming a part thereof.

Figure 1 is a perspective view of a combined catch operator and escutcheon, showing my new design.

Fig. 2 is a side elevational view thereof.

Fig. 3 is a front elevational view thereof, and
Fig. 4 is a front elevational view of the catch operator shown in Figs. 1, 2, and 3, the escutcheon being omitted.

I claim:

The ornamental design for a combined catch operator and escutcheon, substantially as shown.

EARL M. BORCHERS.
